(57) **CLAIM**

The ornamental design for a TV mount bracket, as shown and described.

DESCRIPTION

FIG. 1 is a front view of a TV mount bracket showing the new design;

FIG. 2 is a rear view thereof;

FIG. 3 is a left side view thereof;

FIG. 4 is a right side view thereof;

FIG. 5 is a top side view thereof;

FIG. 6 is a bottom side view thereof;

FIG. 7 is a perspective view of the front, top and left side thereof;

FIG. 8 is a perspective view of the front, top and left side thereof, shown in a partially open configuration; and,

FIG. 9 is a perspective view of the rear, top and right side thereof, in a fully open configuration.

The shade lines in the Figures show contour and not surface ornamentation.
